Dec. 1875

Garrettson Smith and Henry Brown, of Philadelphia, Penn.
assors to

C. S. Collins and C. S. Heath, of Baltimore, Md.

Letters Patent No 1875-Dated Dec. 1st 1868.

Design for a Fire-place Stove.

The schedule referred to in these Letters Patent and making part of the same.

To all whom it may concern,

Be it known that we, Garrettson Smith and Henry Brown, of Philadelphia, County of Philadelphia, State of Pennsylvania, have invented or produced a new and original design for a Fire-place Stove; and we do hereby declare the accompanying drawing with the following explanation of the same to form a full, clear and exact description of the said Design.

Fig. 1 of the annexed drawing is a front view of the fire-place stove, and Fig. 2, a perspective view.

Upon the base C, which encloses the ash box

Dec. 1875

rest the three vertical cylinders A and B, the lower portion of the former being surrounded by a semi-annular casing D, in which are a number of open spaces, each of the latter being divided by a pillar L, into two openings which are arched at the top - the whole being ornamented in the manner shown in the drawing.

On the top of the casing D is the ornamented moulding a, above which is the arched door frame G, the latter being ornamented with the mouldings and bosses shown.

The outer edge of each of the doors H is surrounded by a plain moulding b; the foliated ornaments, c, surrounding the opening in each door.

On the front of the cylinder B, and near the base of the same, is a rosette ornament R.

On the edges of the upper and lower plates I and I', of the base C, is a moulding m, composed principally of a series of bosses, and around the base of each of the cylinders A, and B, B is an annular ornamented ridge m.

The sliding doors J in front of the ash drawer, are ornamented as shown in the drawing, and beneath these doors is a row of ornamental bosses o.

On the front of the base C, at each side of the drawer K, is an ornament K' with a central boss.

On each side of the plate E, which fits into the fire place in front of the stove, is a plain moulding F, in the centre of which is an ornamental beading s, the said moulding being continued around the edge of an arched opening cut in the said plate E, each upper corner of the plate having a foliated ornament L.

Near the inner edges of the arched open-

ing in the plate H, and on each side of the stove is a pillar k, having an ornamental base and capital, the latter being surmounted by a foliated ornament M, which follows the curve of the arched moulding E. The foliated ornaments M, on each side of the stove meet at the centre of the arch, where there is an ornamented shield W, enclosing an ornamented cross as shown in the drawing.

We claim: The ornamental figures and forms represented in and by the accompanying drawing, the whole forming an ornamental design for a fire-place stove.

In testimony whereof, we have signed our names, to this specification in the presence of two subscribing witnesses.
